(57) **CLAIM**

The ornamental design for a dispenser for pourable materials, as shown and described.

DESCRIPTION

FIG. 1 is a perspective view of a dispenser for pourable materials showing our new design.

FIG. 2 is a side view thereof.

FIG. 3 is a side view in alternate position.

FIG. 4 is a rear view of FIG. 1.

FIG. 5 is a front view of FIG. 3; and,

FIG. 6 is a rear view with alternate environmental subject matter.

The broken lines in the drawings are included for the purpose of illustration and form no part of the claimed design.

This invention relates to a device that has been designed and fabricated to enable the safe and controlled dispersion of pourable materials, such as pourable granules, pourable powders, oils, liquid shortenings, salad dressings and other materials commonly shipped in bulk containers.
